JOHN PRIMROSE, OF DONGAN HILLS, NEW YORK, ASSIGNOR TO POWER SPECIALTY COMPANY, OF NEW YORK, N. Y., A CORPORATION OF NEW YORK

METHOD OF AND APPARATUS FOR CRACKING PETROLEUM OIL

Application filed January 11, 1923. Serial No. 611,932.

This invention relates to a novel method of destructive distillation of petroleum oils and apparatus therefor. Heretofore the process of cracking has been extensively utilized for the production of lower from higher boiling point oils. One method of carrying out such a process has been to pass the petroleum oil through a tubular heater resembling an ordinary water tube boiler and having a number of rows of tubes disposed one above another. These tubes are disposed above a furnace and the hot gases of combustion sweep across the tubes and heat the oil contained therein to the desired cracking temperature. The cracking temperature employed varies with different processes but for purpose of explanation the temperature of 765° F. can be taken as a typical one. When petroleum is subjected to a sufficient degree of heat the molecules of oil are cracked into components which may be briefly stated to be free carbon, fixed gas and the desirable light and intermediate products together with a proportion of heavier fractions. Experience has demonstrated that the heat absorption and temperature conditions must be very carefully controlled to provide for the maximum quantity of the desirable products. If the oil passing through the tubes absorbs heat at an excessive rate the oil film lying next to heating surface is cracked beyond the desired degree with the result of a loss in yield of lower boiling point products and an excessive formation of carbon and fixed gases. A portion of the carbon thus formed will adhere to the surface of the metal and will form a film upon the inside of the tubes particularly at the points where there is an excessively high rate of heat absorption, which film will act as a heat insulator between the oil which acts to carry away the heat and the metal of the tube, allowing an overheating of the tube at such points. Eventually a point will be reached in which the tubes subject to the higher rates of heat absorption are excessively or even entirely clogged with carbon. Even before such a stage is reached the accumulation of carbon in the tubes may be such that hot spots

would develop in the tubes if the operation were continued. For this reason it has heretofore been the practice to shut down the heating units when a comparatively thin film of carbon had been formed in the tubes. 55 Each of these shut downs necessitates the cooling down of the unit, the withdrawal of the oil and the cleaning of the tubes or replacement of same. Then, in putting a unit back into service, the oil must be replaced therein and the unit heated up to the desired temperature before the process of cracking can be recommenced. 60

From the foregoing it is seen that localized overheating must be avoided and the 65 temperature of the metal tube maintained as low as possible if the desired maximum of efficiency and capacity are to be obtained.

It has been further found that for the best results in the cracking processes that 70 the range of temperature is very small. This point is covered by Bureau of Mines Technical Paper No. 258 in which it is stated that this range is "considerably less than 50° C." This again emphasizes the importance of 75 accurate control of the temperature of the metal tube.

In absorbing heat by oil passing through a metallic tube the temperature of the metal tube bears an important relation to the 80 cracking results which are obtained within the tube. Conditions of rates of absorption above those actually required for cracking oil will cause an excessive formation of carbon and fixed gases. This condition is 85 particularly aggravated in the treatment of distillates from asphaltic base oils such as from California crudes.

The ideal condition for cracking oil would be to bring all points of the oil within the heating unit to a desired and uniform 90 cracking temperature. This, however, is impossible where heat is supplied to the oil by hot metal surfaces such as those in any heater having conduits through which oil is passing. In order to realize the nearest practicable approach to the ideal condition, the heat must be so supplied to the oil as 95 to maintain a substantially equal rate of heat transfer from all portions of the unit 100

to the oil without exceeding a predetermined temperature difference between the inside surface of the conduits and the oil in any section of the conduits anywhere within the heating unit.

5 The above briefly indicates the desirability of the proper control of the rate of heat absorption by the oil, which is equal to the rate of heat transfer through the tubes, and 10 also the necessity and desirability of preventing overheating. Summarizing, it may be stated that a certain temperature and rate of heat absorption must be reached before obtaining a proper yield of the desirable products. Secondly, this oil temperature and the corresponding rate of heat absorption should not be exceeded to any material degree otherwise the quantity of desirable products will be decreased and there 15 will be an undesirable and deleterious formation of carbon and fixed gas. Third, the method and construction employed should be one which should permit a high over all heat efficiency. Fourth, the necessity for 20 shut downs should be brought to a minimum.

In practice it has been demonstrated that when petroleum oil is cracked in a heater embodying a plurality of superimposed 25 tubes, the tubes which are exposed to the direct or radiant heat of the fire or furnace absorb a far greater amount of heat than the tubes which absorb heat from the gases by convection. The absorption of heat by 30 the oil is attained in two ways: first, by absorption of direct and radiant heat energy and second, by absorption of heat by convection. With an ordinary type of heater the lower tubes are usually exposed to this 35 direct or radiant heat. The furnace walls become highly radiant and this radiant energy impinges upon the lowermost halves of the lowermost tubes. In a given apparatus, for example, provided with nine superimposed rows of tubes it was observed that of 40 the heat absorbed, the lowermost row received so much heat by direct and radiant energy, that these tubes alone effected 70% of the heat absorption, leaving the balance 45 of eight rows of tubes together to absorb the remaining 30%. Consequently, when such a heater is used for cracking and the proper quantity of heat is supplied to the heater to effect the cracking of oil at a given 50 rate the lower tubes will absorb heat too rapidly and the rows of tubes above will not absorb heat at an efficient rate. Furthermore with such a heater there will be an excessive deposition of carbon and an 55 excessive formation of fixed gas in the lower tubes. In order to minimize such conditions arising it has been heretofore necessary to cut down the furnace temperature and this 60 has usually been accomplished by admitting 65 excess air with the heating fuel. The use

of this excess air has materially reduced the efficiency of such heaters since a large proportion of the heat of combustion is utilized in raising the temperature of excess air. With the utilization of only sufficient air for 70 complete combustion, much higher furnace or heating efficiency is attainable.

The present invention is directed to a novel method and apparatus for cracking petroleum oils to the general end that the 75 rate of heat absorption in the various parts of the apparatus may be made substantially uniform and effectively controlled so that the ideal rate of heat absorption may be obtained in each part of the apparatus. 80 The result is that the entire apparatus may be operated under ideal conditions for cracking, the production of the maximum quantity of the desirable products under which conditions a maximum length of run with- 85 out shutting down of the apparatus is secured and with the obtaining of the maximum yield of the desirable products and a minimum of carbon and fixed gas from a given oil. Further, such a regulation of the 90 heat distribution will make possible high heat efficiency in the heating apparatus.

A further object of the invention is the control of the heat distribution in such a way as to compensate for both the intensity 95 of the direct and radiant heat and for the comparative sluggishness of transfer of heat by convection from hot gases to the general end that the oil receiving heat by radiation will not be overheated and that the 100 oil receiving heat by convection will be heated to the proper degree.

The invention can be best illustrated by reference to the drawings which illustrate a preferred embodiment of the apparatus 105 by which the process can be carried out.

In the drawings,

Fig. 1 is a central vertical section of the apparatus.

Fig. 2 is a top plan view of the same.

Fig. 3 is a detail view of certain of the conduit casings.

Fig. 4 is a diagrammatic view of a complete apparatus.

According to the present invention I provide an apparatus which generally consists of two chambers as shown in Fig. 1, one a furnace chamber 10 and the second a so-called heating chamber 11. This structure is built up in the usual way with fire brick 115 and the furnace chamber is separated from the heating chamber by a bridge wall 13 which is preferably hollow. The fuel for providing a source of heat is burned in the furnace chamber in any desired manner, as 120 by a burner, indicated diagrammatically at 14. A suitable quantity of air to support combustion may be admitted from below and controlled in any desired manner, as by damper 15. The arrangement of the bridge 125

110

115

120

125

130

wall and of the heating and furnace chambers is such that the direct radiations from the heated walls of the furnace chamber and from the flame are prevented from impinging upon the roof portion of the heating chamber, either directly or by reflection. In order to secure this result the bridge wall is preferably made of a considerable thickness. When the furnace is in operation the hot gases of combustion pass over the bridge walls through the conduit 16 and thence downwardly into the heating chamber 11, finally emerging through the outlet duct 17 to the stack.

15 *Furnace chamber*

During the operation the walls of the furnace chamber become highly heated, and eventually attain a condition of radiance. 20 In order to utilize this radiant energy in the furnace chamber without excessive absorption of heat by portions of the oil which are to be cracked, I provide a plurality of conduits 18. In practice these conduits may 25 be placed in the roof of the furnace as well as the front or side walls or even in the bridge wall. The number of conduits which are to be used and their relative location in the furnace chamber or their omission 30 from one or more of the walls or roof will depend upon the operating demands of the cracking process. If these conduits were directly exposed to the radiant heat of the furnace chamber itself and of the flame 35 therein the oil flowing through the conduits or tubes would absorb heat at an excessively high rate and there would be the undesirable results heretofore explained. To obviate such results I provide protecting casings 19 40 of refractory material surrounding these tubes. The thickness and character of these casings will be such that the high temperature heat radiations will be received upon the outer surface of the casings and the 45 heat thereof conducted through the casings and imparted to the tubes at a reduced temperature whereby the oil within the tubes will not absorb heat at an excessive rate but at a rate which is suitable for the highest 50 yield of the desirable products.

By the provision of suitable oil conveying, heat receiving conduits in the furnace chamber, I not only reduce the temperature of the gases passing from the furnace chamber 55 through the conduit 16 but I also usefully recover the heat and utilize the same in the cracking process. It will thus be seen that the temperature of the gases entering the heating chamber may be so reduced that the 60 walls of the heating chamber do not attain a condition of radiance from the heat of the gases. The conduits 18 with the oil contained therein, serve the purpose of absorbing radiant heat so that the tubes 20, to be 65 hereafter described, and the oil therein will

not be subject to the combined cumulative effects of heat of radiation and heat of convection.

Heating chamber

The absorption of heat in the heating chamber is effected substantially only by convection. Consequently, as the gases impart heat to successive exposed surfaces the temperature of the gases will fall and less and less heat will be given up by them other conditions being equal. As it has been heretofore pointed out all parts and all heat absorbing surfaces should receive heat at substantially an equal rate. I therefore provide a means for distributing and equalizing the rate of heat absorption in the heating chamber as will now be described.

Preferably within the heating chamber there are provided a series of superimposed wrought iron or steel tubes 20. The individual tubes are provided with suitable casings of cast iron. Preferably the upper row of tubes which are subject to the hottest gases are provided with plain cylindrical casings 21. The tubes which are later traversed by the heated gases are provided with corrugated cast iron casings 22. Details of the cast iron casings are shown in Fig. 3. I also vary the depth of the corrugations in such a manner that the exposed heat absorbing surfaces are substantially in inverse proportion to the temperature difference between the hot gases and the oil within the tubes. As shown, the corrugations are shallower on the tubes nearer the top of the heating chamber and become greater and greater in depth as they approach the lowermost rows. The exact arrangement of corrugations and the number of rows of plain cylindrical casings to be employed, if any, will depend upon the particular operating characteristics of the individual heater. Furthermore the ability of the hot gases to impart heat is nearly directly proportional to the velocity of the gases themselves. This factor is of course taken into consideration in designing the corrugations of the casings to the general end that the desired transfer of heat will be made uniform on all of the 100 tube sections of the heater.

Substantially uniform distribution of heat is obtained around the entire periphery of the tubes subject to radiant heat by means of the refractory protective casings which not only cut down the transmission of heat to the oil within the tube but also serve to distribute the heat and the temperature 110 equally about the tube periphery.

The smooth and corrugated metallic casings which are disposed upon the tubes which are traversed by the hot gases and which absorb heat by convection therefrom serve in a similar manner. These heat absorbing elements take up the heat from the 120 130

hot gases and impart the same to the tube and in doing so equalize the temperatures about the periphery of the tubes.

By the provision of the refractive coverings and the corrugated heat absorbing surfaces conditions of rates of heat absorption may be effectually controlled to the general end that the excessive formation of carbon and fixed gas is minimized. Furthermore the distribution and transfer of heat to the oil may be so controlled that all units of the surfaces supply heat at substantially the same rate.

It is not deemed necessary here to describe in detail the arrangement of header connections for the various conduits. These can be arranged as individual conditions necessitate, and the oil can be arranged to flow through the conduits in series or in multiple or series-multiple paths as desired.

In the system herein illustrated it is contemplated that the oil enters the system in a highly heated condition. It will be understood, however, that the oil may be fed to the system in a cool or cold condition, in which case, certain heating surfaces in the system are employed for bringing the oil up to the cracking temperature and the maximum allowable temperature difference condition does not apply necessarily to that portion of the heat absorbing surface which is used for preheating the oil. No detrimental effects will result from the high rates of heat transfer in this preheating portion of the heating system because no cracking takes place until certain critical temperatures are reached.

In certain instances it may be desirable to operate with such high temperatures of the gases entering the heating chamber that the exposed walls will become slightly radiant. In such instances the effect of this radiant heat upon the uppermost tubes within the heating chamber may produce slight overheating of the oil contained therein unless provision is made for eliminating destructive heat radiations. For this purpose I may provide oil conveying tubes or conduits 23 in the roof of the heating chamber 11. These tubes are preferably provided with cast iron protective casings 24 which cooperate to prevent a transfer of radiant heat energy from the roof to the upper tiers of tubes 20. Similar oil conveying tubes 25 may be placed in the walls of the heating chamber above the transverse heating elements and these tubes 25 may be covered with refractory or cast iron casings 26 depending upon the individual prevailing conditions. In the drawings, refractory casings are illustrated and they serve the purpose of protecting the tubes in the wall from the possibility of being over-heated when operating under such high temperatures as would cause the exposed walls of the fur-

nace chamber to become radiant. The principal destructive heat radiation with high temperature conditions in the heating chamber is between the opposed heat absorbing surfaces. By providing the opposing heating surfaces 21 and 24 destructive heat radiations are prevented from impinging upon either the upper row of tubes 20 or tubes 23 in the roof. These tubes 23 are here shown as extended from and forming a continuation of the tubes or conduits 18 in the roof of the furnace chamber. The extension of the conduits 18 at 23 over the top of the heating surface 20 and the cooperating side conduits 25 together with the oil therein serve to absorb heat, if at any time, high intensity radiant heat conditions tend to be built up in the heating chamber. These radiations are absorbed and protection is thus afforded under these conditions against objectionable cumulative overheating due to the combined heat of radiation and heat of convection acting by conduction upon the oil of the upper of conduits 20. The present application is a continuation in part of the subject matter of my copending application Serial No. 482,135 filed January 2, 1921 and now patented, Patent No. 1,568,182 dated January 5, 1926.

The direction of flow of oil through the various sections, stages and zones of the heater is largely a matter of selection and design. As here illustrated the radiant heat absorbing stage or zone is divided. Oil entering the system flows through the walls of the furnace chamber absorbing radiant heat, thence through the conduits 20 where heat is absorbed by convection from the hot gases and finally flows back through the roof tubes 18 where further radiant heat is absorbed. The particular flow conditions may be reversed or the order changed as desired. From the heater the oil flows to a suitable condenser and evaporator.

Fig. 4 shows diagrammatically a complete system including heater H, evaporator E, dephlegmator D, circulating pump P and condenser C. These parts of the system may be of any desired type.

The direction of flow of the oil through the various sections of the furnace is largely a matter of selection and design. If desired the oil can flow through the tubes in the heating chamber first and thence through the other tubes or if desired the flow conditions may be reversed.

It will be apparent that there will be a zone in the heating system where the radiant and direct heat as well as the heat by convection are factors in the heat absorption. Substantially, however, the heating system is divided into the two distinct zones or stages as described, and this invention is not limited by lack of a complete analysis of such obvious conditions or inessential details

which would only tend to burden the specifications and obscure the important elements in the process.

What I claim is:—

5 1. A method of cracking petroleum oil which comprises passing the oil through a plurality of conduits, subjecting the oil to cracking temperature in a multistage heating process, in one stage supplying heat to the oil by radiant heat and in another stage supplying heat to the oil primarily by heat of convection, and maintaining substantially uniform and equal the rate of heat absorption in the various stages.

15 2. In the method of cracking petroleum oils, the improvement which consists in conducting oil to be cracked through a plurality of metallic conduits, heating the oil progressively to cracking temperature by radiant heat in certain of said conduits and heat of convection in other of the conduits, and providing a substantially uniform rate of heat absorption throughout to give a substantial uniformity of the cracking action 25 by limiting the heating effect by convection in some parts of the system and limiting the heating effect by radiation in other parts of the system.

30 3. The method of cracking petroleum oil which comprises passing the oil to be cracked through a plurality of conduits, heating the oil to crack the same by absorbing heat by the conduits from gases of diminishing temperatures and thereby heating the oil which 35 is to be cracked, and in providing substantial uniformity of the cracking action by substantially equalizing the rate of heat transfer to the oil from the gases of various temperatures.

40 4. An apparatus for cracking petroleum oil comprising in combination, a plurality of conduits, means for conducting the oil to be cracked therethrough, certain of said conduits being disposed to receive heat by radiation, means comprising refractory protective coverings on said last mentioned conduits for limiting the rate of heat transmission to avoid temperatures in the metal to which the oil is exposed, of such degree as to cause excessive formation of carbon and fixed gases, certain others of said conduits being disposed to receive heat by convection from hot gases, said first mentioned conduits adapted to absorb sufficient heat to decrease the temperatures of the gases of combustion flowing to the second mentioned conduits below a temperature at which excessive carbon and fixed gases form, and 50 means comprising smooth and corrugated metallic casings on said second mentioned conduits to distribute the heat completely around the periphery of the conduits, said smooth casings being disposed in the region of hottest gases and the corrugated casings

increasing in exterior area as the gas temperatures decrease.

5. In an apparatus for cracking petroleum oil, a source of heat, a plurality of oil containing conduits subject to the heat from 70 said source, certain of said conduits being disposed in the path of hot gases from said source, outside corrugations on said last mentioned conduits having extended heat absorbing surfaces so proportioned as to 75 compensate for diminishing temperatures of the hot gases whereby a substantially uniform rate of heat transfer will occur in all parts of said conduits, certain other conduits being oppositely disposed to the last 80 mentioned conduits as to substantially prevent the destructive effects of radiant heat upon the opposing surfaces of the conduits.

6. In an apparatus for cracking petroleum oil, in combination with a source of heat, a plurality of oil-containing conduits subject to heat from said source, certain of said conduits being disposed without the path of the hot gases from said source and receiving radiant heat only, said conduits having refractory material therearound to limit the rate of heat transfer thereto, other of said conduits being disposed in the path of hot gases, the outside surface of said conduits having exterior corrugations constituting an extended heat absorbing surface, said surface being so proportioned as to 90 compensate for diminishing gas temperatures and to substantially equalize the rate of heat transfer to the various conduits 95 which receive heat from the hot gases still other of said conduits being oppositely disposed to the last mentioned set of conduits so as to substantially prevent destructive effects of radiant heat on the opposing surfaces.

In testimony whereof I hereto affix my signature.

JOHN PRIMROSE.
